United States Patent Office.

GEORGE W. PRUYNE, OF MEXICO, NEW YORK.

Letters Patent No. 77,653, dated May 5, 1868.

IMPROVED CHANNELLING-TOOL.

The Schedule referred to in these Letters Patent and making part of the same.

TO WHOM IT MAY CONCERN:

Be it known that I, GEORGE W. PRUYNE, of Mexico, Oswego county, and State of New York, have made new and useful Improvements in "Channelling-Tools," for harness-makers' or other leather-workers' use; and I hereby declare the following to be a full and exact description of the same, reference being had to the drawings that accompany and form a part of these specifications.

The object of my invention is to provide a tool for cutting an even channel in leather, for stitching, when we desire to have the stitches covered and out of sight.

Figure 1, perspective view.

Figure 2, sectional view, showing the form of the slide, and manner of operating the same, and how the knife is held in position.

Letter A, lower part of the tool, in which a slot, *e*, is formed, to insert the knife, and the slide by which the knife is held in place.

Letter B, slide that holds the knife, and also forms one of the shoulders or guides necessary to control the tool and secure an even channel.

Letter C, handle, the lower ends forming a set-screw, that operates the slide B.

Letter D, knife.

The knife is placed in the lower part of the slot *e*, and can be adjusted to cut any depth, the slide B, by the operation of the set-screw C, holding it at any point desired. The part extending below the knife forms a shoulder and guide, to be placed against the edge of the leather.

By reference to the drawings, the application of the tool will be readily seen. Placing the tool upon the corner or edge of the strap in which we wish to make a channel, we find the slide B forms a guide, running on the top, and the extension below the slot *e* a guide, running on the edge of the strap, the knife extending at an angle between the two, and, as we push it along, it cuts a channel true and even in depth.

What I claim, and desire to secure by Letters Patent, is—

The slide B, so constructed as to serve the double purpose of holding the knife and forming a shoulder or guide for the tool, in connection with the part A, substantially as described and set forth.

The handle C, forming a set-screw, and acting in combination with the part A and slide B, substantially as described, and for the purposes specified.

In testimony whereof, I have signed my name to this specification in the presence of two subscribing witnesses.

GEO. W. PRUYNE.
